M. HERSKOVITZ

ADJUSTABLE STRAP FOR ELECTRIC LIGHTING FIXTURES

Filed June 4, 1924

Inventor:
Max Herskovitz,
by Chase & Warner
New York

UNITED STATES PATENT OFFICE.

MAX HERSKOVITZ, OF CHICAGO, ILLINOIS; WILLIAM HERSKOVITZ AND CHARLES WEINFELD EXECUTORS OF SAID HERSKOVITZ, DECEASED.

ADJUSTABLE STRAP FOR ELECTRIC-LIGHTING FIXTURES.

Application filed June 4, 1924. Serial No. 717,696.

To all whom it may concern:

Be it known that I, MAX HERSKOVITZ, a citizen of the United States, and a resident of Chicago, Cook County, and State of Illinois, have invented certain new and useful Improvements in Adjustable Straps for Electric-Lighting Fixtures, of which the following is declared to be a full, clear, and exact description.

10 This invention relates to adjustable supporting straps for electric lighting fixtures and its principal object is to provide an adjustable metal strap, whereby it will fit mostly all electric lighting fixtures. An 15 other object is to provide a strap for electric lighting fixtures having adjustable features whereby the fixture, supported thereby, may be placed off centre with respect to the stud or pipe upon which the strap is secured. 20 Another object is to reduce the number of parts of adjustable supporting straps for electric lighting fixtures to a minimum.

With these and other objects and advantages in view, this invention consists in 25 the several novel features hereinafter fully described and claimed.

The invention is clearly illustrated in the accompanying drawing in which:

Fig. 1 is a side elevation, partly broken 30 away, of an adjustable strap for electric lighting fixtures showing the same in use supporting a ceiling light; Fig. 2 is a perspective view of the strap; Fig. 3 is a plan illustrating a number of the end member 35 blanks showing how they are punched; Fig. 4 is a detail section taken on the line 4—4 of Fig. 2; Fig. 5 is a plan of a slightly modified form of the centre member of the strap and Fig. 6 is a side elevation, partly 40 broken away, showing the application of the strap to a wall bracket.

Referring to said drawing and first to Figs. 1 to 4 inclusive, which illustrate the preferred embodiment of the invention, the 45 reference character 7 designates an outlet box of ordinary form, 8 the threaded fixture supporting stud thereof, 9 the strap which forms the subject matter of this specification, 10 the globe or shade holding collar, 50 and 11 the globe or shade which is supported by the collar 10. An ordinary electric light socket may be fastened to the stud by the usual method or it may be otherwise fastened to the ceiling which supports the fixture.

In its preferred form, the strap comprises two similar fixture supporting end members 12, 12 adjustably connected by a fitting or centre piece 13. Each end member 12 comprises a forked piece formed of sheet metal 60 having a neck portion 14 and two spaced parallel branches 15 extending therefrom. The neck portion 14 is punched and struck up to form a hole 16, the edge of which is threaded for the reception of a bolt or screw 65 17 which is used to secure the collar 10 to the strap. It may also be punched with a bolt hole 14^a for use in attaching certain fixtures to the strap. The branches 15 of each end member 12 are struck up with suitable dies 70 to form ribs or beads 18 for the purpose of giving strength and rigidity to the branches. The branches of one end of member 12 are placed upon those of the other end member 12 as seen in Fig. 2 and they are adjustably 75 connected together by the fitting or centre piece 13. Preferably said centre piece is channel shaped and the flanges 19 thereof are slotted as at 20 to receive the overlapping branches 15 of the end members 12. 80 The main part 21 of the centre piece is formed with a hole 22 whereby it may be slipped upon the threaded pipe or other supporting stud 8. The strap is secured to said pipe or stud by a nut 23 or by an electric 85 light socket threaded on the stud and screwed up against the under side of the centre piece 13.

The free ends of the branches 15 are formed with small projections 24 which may 90 be bent up after the three parts of the strap have been assembled, thereby forming lugs which prevent the several pieces from being detached from each other during the handling or shipping of the strap and thus 95 eliminating the use of many pieces.

The end pieces 12 are punched out of a strip or sheet of metal and the branches of one end member are punched out of the metal occupying the spaces between the 100 branches of two adjacent branches, as is clearly seen in Fig. 3, whereby very little material is wasted in the formation of the end pieces, thereby making it possible to produce the strap economically.

By making the two end members adjustable, the strap may be accommodated to collars or canopies of various sizes within given limits, and because of the adjustability of the centre piece on the two end members.

said centre piece may be located at any point along the branches 15 between the lugs 24, whereby the fixture may be supported off centre with respect to the pipe or stud which carries it.

In use the centre piece of the strap is slipped over the pipe or stud 8 and the nut 23 or electric light socket is screwed up against the lower side thereof. The end members 10 12 may then be adjusted in the centre piece to bring them at the places desired, the collar or canopy 10 is then placed over the strap and is secured thereto by the screws 17.

In the form illustrated in Fig. 5 the centre piece 13^a is made considerably longer than that seen in Fig. 2 and it is formed with slots 13^b and bolt holes 13^c, whereby many different forms of fixtures may be secured thereto. Instead of the transversely extending flanges 19 of the centre piece of the preferred form, the centre piece is formed with flanges 19^a that run lengthwise of the centre piece and have bent end portions that lie parallel with the main part or body of the centre piece to form guide ways for the reception of the branches of the end members.

In Fig. 6 I have shown the strap 9 secured upon a wall and have illustrated an ordinary wall bracket 11^a supported by the strap in an off centre condition with respect to the supporting stud. In case it is desired to move the bracket from the centre the end members 12 are adjusted to the place desired.

In case it is necessary to fit the strap to a bracket or other fixture of very small diameter the arms 15 may be cut by a pair of snips.

More or less variation of the exact details of construction is possible without departing from the spirit of this invention; I desire, therefore, not to limit myself to the exact form of the construction shown and described, but intend, in the following claims,

to point out all of the invention disclosed herein.

I claim as new and desire to secure by Letters Patent:

1. An adjustable strap for lighting fixtures, comprising a centrally apertured centre piece formed with flanges, and two similar fixed supporting members, each having two spaced branches, the branches of one end member overlapping the branches of the other member and both being held by the flanges of said centre piece. 55

2. An adjustable strap for lighting fixtures, comprising an apertured centre piece formed with slotted flanges, and two similar fixture supporting end members, each formed with a neck portion and two parallel branches, the branches of one member overlapping those of the other and all branches extending through the slots of the slotted flanges of the centre piece and being adjustably secured therein. 60

3. An adjustable strap for lighting fixtures, comprising a centrally apertured, flanged centre piece, and two similar fixture supporting end members, each formed with a neck and two spaced parallel branches, 70 the branches having struck up beads or ribs formed thereon and their ends being formed with laterally extending lugs, the branches of one end member overlapping those of another and being slidably held by the 75 flanges of the flanged centre piece.

4. An adjustable strap for lighting fixtures, comprising three members assembled together so as to be adjustable upon each other, and one formed with a hole whereby 80 it may be slipped upon a stud or pipe, and the other two being formed with struck up lugs arranged to strike against the first mentioned member to prevent disconnection between the members.

MAX HERSKOVITZ.
